UNITED STATES PATENT OFFICE.

HENRY LLOYD WEISS, OF GARY, WEST VIRGINIA.

ENVELOP.

1,287,804.

Specification of Letters Patent. Patented Dec. 17, 1918.

Application filed June 8, 1918. Serial No. 233,870.

To all whom it may concern:

Be it known that I, HENRY LLOYD WEISS, a citizen of the United States, residing at Gary, in the county of McDowell and State 5 of West Virginia, have invented new and useful Improvements in Envelops, of which the following is a specification.

This invention relates to an improved form of check protector and the principal 10 object of the invention is to provide means for protecting checks of persons not provided with the mechanical protectors.

Another object of the invention is to provide a covering means for the check to prevent the same from being "raised" but permitting the same to be indorsed, said covering means being removed by the cashier of 15 the bank.

Another object of the invention is to provide a device of this character which is simple and durable in construction, reliable and efficient in operation and one which can be manufactured and placed upon the market at a minimum cost.

25 The invention also consists in certain other features of construction and in the combination and arrangement of the several parts, to be hereinafter fully described, illustrated in the accompanying drawings 30 and specifically pointed out in the appended claims.

In describing my invention in detail, reference will be had to the accompanying drawings wherein like characters denote like 35 or corresponding parts throughout the several views, and in which:—

Figure 1 is a view of the rear side of the envelop forming the subject matter of the present invention.

40 Fig. 2 is a face view thereof.

As shown in these views the invention is in the form of an envelop 1 made of transparent material and having one end open. The face of the envelop at this open end is 45 provided with a tab 2 provided with a rounded free end 3 which may be coated with adhesive material. The other face of the envelop adjacent said open end is provided with an opening 4 which is engaged 50 by said rounded end when the pad is folded over, so that the adhesive material thereon will come in contact with the check within the envelop. I prefer to make this tab of

tough transparent paper of a different color from that of the envelop. I locate seals 5 55 around the edges of the envelop of like material to that of the tab and said seals are doubled to engage both the front and rear faces of the envelop. As shown, these seals are placed on the side and the rear end edges 60 of the envelop. Adjacent the rear end of said envelop on the rear face thereof I form an oblong slot 6 so that the check may be indosed therethrough without removing the 65 check from the envelop.

I place on the rear face of the envelop the words "To be opened by cashier only", or similar words with a space for the signature of the person issuing the check.

After the check is written it is placed 70 within the envelop and sealed therein by means of the tab 2 having its end moistened and secured to the rear face of the envelop and the check through the opening 4. The payee may readily read the check through 75 the transparent envelop and he may indorse the same through the slot 6. When he presents the same to the bank the cashier can readily see that the check has not been tampered with owing to the seals being unbroken and he may remove the check from the envelop and treat it as usual. In this way it is impossible for the amount of the 80 check to be raised.

It is thought from the foregoing description that the advantages and novel features 85 of my invention will be readily apparent.

I desire it to be understood that I may make changes in the construction and in the combination and arrangement of the several 90 parts, provided that such changes fall within the scope of the appended claims.

What I claim is:—

1. A check protector comprising a transparent envelop, means for sealing the check 95 in said envelop and said envelop having an indorsing opening therein.

2. A check protector comprising a transparent envelop having one end open for receiving the check and provided with a sealing opening adjacent said opening and an indorsing opening adjacent the other end 100 and a sealing tab engaging with said sealing opening.

In testimony whereof I affix my signature. 105
HENRY LLOYD WEISS.
